In Germany November 11, 1935

3 Claims. (Cl. 179—171)

This invention relates to a high frequency amplifying arrangement which allows the passage of a very broad frequency band having a width of say 4000 kilocycles sec. such as are used, inter alia, in television.

When an alternating voltage is set up between the control grid and the cathode of an amplifying tube, whose anode circuit comprises a tuned oscillatory circuit, the voltages occurring through this oscillatory circuit being supplied to a succeeding amplifying stage, then the amplification of such an arrangement greatly depends on the frequency. A comparatively narrow frequency band is allowed to pass highly amplified, whereas the amplification is low for all of the other frequencies.

As is well-known, a flat course of the frequency characteristic curve of such an amplifier can be ensured by connecting a damping resistance in parallel with the oscillatory circuit. According as to whether the circuit is more damped, the frequency band passing through it will be broader, the amplification decreasing, however, at the same time.

According to the invention, a flat course of the frequency characteristic (uniform amplification for a large frequency spectrum) is ensured in a high frequency amplifying arrangement, in which the anode circuit of one or more amplifying tubes comprises a tuned oscillatory circuit (primary circuit) coupled with a second tuned oscillatory circuit (secondary circuit), by deriving the amplified oscillations from the primary circuit, the primary circuit being slightly and the secondary circuit being strongly damped.

The invention will be more clearly understood by references to the accompanying drawing in which:

Fig. 1 shows a circuit arrangement of a series connection and a self-inductance, a capacity, and a damping resistance connected in parallel with a primary circuit;

Fig. 2 represents a circuit arrangement in which the oscillatory circuits are coupled by a capacitive coupling;

Fig. 3 shows a circuit arrangement in which the two oscillatory circuits are coupled inductively;

Fig. 4 indicates the damping of the secondary

circuit by means of a resistance connected in parallel to the secondary circuit;

Fig. 5 shows a third tuned oscillatory circuit connected in parallel with part of the secondary circuit, the third circuit being connected in parallel with a damping resistance; and

Fig. 6 shows a third tuned oscillatory circuit connected in parallel with part of the secondary circuit, the third circuit being connected in parallel with the series connection of a self-inductance and a capacity.

Fig. 1 shows a circuit arrangement in which a series-connection of a self-inductance L_2 , a capacity C_2 and a damping resistance R_2 is connected in parallel with the primary circuit L_1 , C_1 , the two circuits L_1 , C_1 and L_2 , C_2 , R_2 , C_1 being very tightly coupled.

The operation of this circuit arrangement may be explained as follows. When the reaction of the anode of the amplifying tube may be neglected, the amplification of such a circuit arrangement corresponds to SZ_a , S being the slope of the characteristic of the amplifying tube and Z_a representing the impedance of the anode circuit. Now, the admittance Y_a of the anode circuit in the circuit arrangement represented in Fig. 1 will be:

$$Y_a = \frac{1}{j\omega L_1} + j\omega C_1 + \frac{1}{R_2 + j\omega L_2 + \frac{1}{j\omega C_2}} \quad 30$$

if the damping of the primary circuit is neglected.

For this equation we may write:

$$Y_a = j\omega C_1 \left[1 - \frac{1}{\omega^2 L_1 C_1} \right] + \frac{1}{R_2 + j\omega L_2 \left[1 - \frac{1}{\omega^2 L_2 C_2} \right]} \quad 35$$

Supposing that $L_1 C_1$ and $L_2 C_2$ have been made equal, and

$$\omega = \omega_0 + p; \quad \omega_0 = \sqrt{L_1 C_1};$$

$$\frac{1}{\omega^2 L_1 C_1} - \frac{1}{\omega^2 L_2 C_2} = \frac{(\omega - \omega_0)^2}{\omega^2} \approx 1 - \frac{2p}{\omega} \quad 45$$

Substituting these values, we find:

$$Y_a = 2j\omega C_1 + \frac{1}{R_2 + 2j\omega L_2} = \frac{1 - 4p^2 L_2 C_1 + 2j\omega C_1 R_2}{R_2 + 2j\omega L_2} \quad 50$$

This means that the amplification at the frequency ω amounts to:

$$5 \quad V_\omega = S \sqrt{\frac{R_2^2 + 4p^2 L_2^2}{(1 - 4p^2 L_2 C_1)^2 + 4p^2 C_1^2 R_2^2}}$$

whereas for the resonance frequency we get the amplification $V_0 = SR_2$.

Thus, we find:

$$10 \quad \frac{V_\omega}{V_0} = \sqrt{\frac{1 + 4p^2 \frac{L_2^2}{R_2^2}}{1 + 4p^2 (C_1^2 R_2^2 - 2L_2 C_1) + 16p^4 L_2^2 C_1^2}}$$

$$15 \quad = \sqrt{\frac{1 + a_1 p^2}{1 + a_2 p^2 + b_2 p^4}}$$

15 The flattest course of the frequency characteristic is obtained when a_1 and a_2 are equalized and b_2 is made as small as possible. If these conditions are satisfied at least approximately a very flat frequency characteristic is obtained.

20 When departing from these conditions the frequency characteristic exhibits some maxima and minima, of which use may be made in many cases for securing the passage of a broader frequency band or a stronger amplification.

25 Fig. 2 represents a circuit arrangement in which the oscillatory circuits are coupled by a capacitative coupling, the damping of the secondary circuit being brought about by connecting a resistance R_2 in series with the self-inductance of this circuit.

30 Fig. 3 shows a circuit arrangement in which the two oscillatory circuits are coupled inductively, the damping of the secondary circuit being brought about with the aid of a series resistance R_2 as is also the case in the above-mentioned arrangements.

35 In the circuit arrangement represented in Fig. 4 damping of the secondary circuit is ensured by means of a resistance R_2 connected in parallel with this circuit. If it is found that when such a parallel-connected damping resistance is used the coupling between the two oscillatory circuits is purely capacitative or purely inductive, an asymmetrical frequency characteristic is obtained. A symmetrical frequency characteristic is achieved by coupling the two oscillatory circuits both capacitative and inductively, the capacitative coupling being equal to the inductive coupling.

40 50 The equations for the circuit arrangements represented in Figs. 2, 3 and 4 are similar to those referred to above for the arrangement shown in Fig. 1.

55 When an amplifying arrangement according to the invention is used for television purposes, it is desirable that the frequency characteristic should have a flat course and in addition that for any frequency the phase-displacement brought about by the amplifier should be proportional to the difference between this frequency and the frequency of the carrier wave,

since otherwise deformation of the picture occurs. Consequently, the amplifying arrangement should satisfy the condition that the ratio φ/p is constant throughout the frequency range, where φ represents the phase displacement.

5 The arrangements according to the invention permit this latter condition to be satisfied over a large range of frequencies.

10 A further improvement of the course of the frequency characteristic can be obtained by using the arrangements shown in Figs. 5 and 6, in which a third tuned oscillatory circuit is connected in parallel with part of the secondary circuit. In Fig. 5, this third circuit L_3, C_3 is connected in parallel with the damping resistance R_2 , whereas in Fig. 6, the third circuit is connected in parallel with the series-connection of the self-inductance L_2 and the capacity C_2 . In calculating V_ω/V_0 for the arrangements represented in Figs. 5 and 6, we find the equation:

$$20 \quad \frac{V_\omega}{V_0} = \sqrt{\frac{1 + a_1 p^2 + b_1 p^4}{1 + a_2 p^2 + b_2 p^4 + c_2 p^6}}$$

25 In these arrangements, a flat course of the frequency characteristic is ensured by at least approximately making $a_1 = a_2$ and $b_1 = b_2$, whereas c_2 should be as small as possible.

What is claimed is:

1. A circuit arrangement for amplifying high frequency electrical oscillations comprising a vacuum tube having an anode circuit, said circuit comprising a tuned oscillating circuit, an output circuit connected thereto, a strongly damped tuned circuit in a mutual inductive relationship with said first tuned circuit and capacitatively coupled thereto, the inductive coupling being equal in magnitude to the capacitative coupling.

30 40 45 40 A circuit arrangement for amplifying high frequency electrical oscillations comprising a vacuum tube having an anode circuit, said circuit comprising a tuned oscillating circuit, an output circuit connected thereto, a strongly damped tuned circuit in a mutual inductive relationship with said first tuned circuit and means for capacitatively coupling said circuits comprising a condenser between said circuits, the inductive coupling being equal in magnitude to the capacitative coupling.

50 55 60 55 A circuit arrangement for amplifying high frequency electrical oscillations comprising a vacuum tube having an anode circuit, said circuit comprising a tuned oscillating circuit, an output circuit connected thereto, a second tuned circuit in a mutual inductive relationship with said first circuit and capacitatively coupled thereto, the inductive coupling being equal in magnitude to the capacitative coupling, and means for damping said second tuned circuit comprising a resistance connected across said second tuned circuit.
